KNIT HELMET

Roy E. Stock, 6373 Teller St., Arvada, Colo. 80002

Filed Sept. 6, 1974, Ser. No. 503,974

Term of patent 14 years

Int. Cl. D2—03

U.S. Cl. D2—249

Fig. 1

Fig. 2

Fig. 3

Fig. 4

Fig. 5

Fig. 6

FIG. 1 is a front perspective view of a knit helmet showing my new design;

FIG. 2 is a front elevational view thereof with the chin strap in a fastened position;

FIG. 3 is a side elevational view thereof;

FIG. 4 is a rear elevational view;

FIG. 5 is an elevational view of the side opposite that shown in FIG. 3; and

FIG. 6 is a top plan view.

I claim:

The ornamental design of a knit helmet, as shown and described.
